CLAIM

The ornamental design for a cell phone case with integral scanner and removable battery, as shown and described.

DESCRIPTION

FIG. 1 is an isometric front-left view of a cell phone case with integral scanner and removable battery showing my new design;

FIG. 2 is an isometric front right view of the cell phone case with integral scanner and removable battery;

FIG. 3 is an isometric back-right view of the cell phone case with integral scanner and removable battery;

FIG. 4 is a front view of the cell phone case with integral scanner and removable battery;

FIG. 5 is a back view of the cell phone case with integral scanner and removable battery;

FIG. 6 is a left-side view of the cell phone case with integral scanner and removable battery;

FIG. 7 is a right-side view of the cell phone case with integral scanner and removable battery;

FIG. 8 is a top view of the cell phone case with integral scanner and removable battery; and,

FIG. 9 is a bottom view of the cell phone case with integral scanner and removable battery.

The broken lines in the drawings depict portions of the cell phone case with integral scanner and removable battery that form no part of the claimed design.

1 Claim, 7 Drawing Sheets
